Des. 220,368
Patented Mar. 30, 1971

220,368

COMBINED PHONOGRAPH TURNTABLE AND BASE OR SIMILAR ARTICLE

Lawrence Levow, Huntington, N.Y., assignor to Harman-Kardon Incorporated, Plainview, N.Y.

Filed Oct. 15, 1969, Ser. No. 19,574

Term of patent 14 years

Int. Cl. D14—01

U.S. Cl. D56—4

The single figure is a front and top perspective view of a combined phonograph turntable and base or similar article, showing my new design, the base having substantially the same appearance from the rear and both sides.

I claim:

The ornamental design for a combined phonograph turntable and base or similar article, as shown and described.
